UNITED STATES PATENT OFFICE.

CHARLES M. COEN, OF NEW YORK, N. Y.

APPARATUS FOR THE PROPULSION OF VESSELS.

SPECIFICATION forming part of Letters Patent No. 733,010, dated July 7, 1903.

Application filed October 9, 1902. Serial No. 126,505. (No model.)

To all whom it may concern:

Be it known that I, CHARLES M. COEN, a citizen of the United States, residing at New York, in the county and State of New York, have invented certain new and useful Improvements in Apparatus for the Propulsion of Vessels; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The object of this invention is to provide for the absolute immersion of a propeller-wheel of abnormal proportions as compared with the depth of water wherein the said wheel is to work, so as to secure the propulsive effects or relative benefits of a comparatively large propeller-wheel in places where only light-draft vessels can be used.

The end to which I aim is attained by first inclosing the wheel within the body of the vessel, as hereinafter shown, so that the water can reach the said chamber from forward and discharge from the after portion of the chamber from the action of the wheel. While the top of this chamber is provided with a secondary chamber which is kept sufficiently filled with water to insure the objects herein set forth—that is to say, from the upper side of the wheel-chamber—the air is kept partially or wholly free by exhaustion, so that 35 as air finds its way into the lower chamber as it enters with the water it ascends to the adjoining chamber, from whence it is taken up by vacuum or partial vacuum therein produced through the ejection of air by steam-pressure or by suction through the use of suitable pumps, as hereinafter more particularly set forth.

I am aware that propeller-wheels have been used in chambers to accomplish the purpose for which I have herein made practical provisions, so as to overcome difficulties which have heretofore rendered attempts in these directions futile. In other words, I provide a separate (overhead) chamber through which 45 the accumulating air during the process of propulsion is eliminated and which would otherwise render the wheel correspondingly

inoperative through racing, as would be the case with any propeller-wheel when only partially immersed. The preferred height of 55 water in this chamber is indicated by a glass water-gage (marked W) connected therewith, as shown.

My final object is to produce here a complete propelling apparatus which can be easily 60 adjusted to light-draft vessels wherein the screw-propeller could not be used, as ordinarily employed in vessels, and thereby make serviceable as independent carriers many boats which have to be towed by other vessels at the present time.

With reference to the accompanying drawings, Figure 1 represents a vertical longitudinal section of the apparatus through the line x, Fig. 3. Fig. 2 represents a top view of 70 the vacuum-chamber and its base as located in a vessel, shown in outline from the top, with dotted lines showing the location of flange of main chamber and incidentally the location of this chamber within the vessel. 75 Fig. 3 represents a vertical section of the apparatus through the line z, Fig. 1.

The dotted lines shown in Fig. 3 are to represent the outlines of a vessel of greater width than the one represented in Fig. 1 of 80 the drawings, all of which in proportion to the size of the propelling apparatus herein shown might seem too insignificant in capacity, as where the same is intended for carrying more than a very limited cargo. In this connection it should here be stated that the apparatus herein described is to be of such an adjustable nature as to admit of being placed in various forms of vessels with no more change than may be found necessary in the 85 making of the bottom walls of the main chamber to fit and fasten to the floor of the vessel by means of flanges herein provided.

In the drawings, A represents an oblong bottomless chamber with arched top, in 95 which is an opening leading to vertical chamber B, which is in turn supplied with a valve C at its top, as shown. This latter chamber I have designated as the "vacuum-chamber," because when in operation a vacuum or partial vacuum is maintained at the upper portion thereof in order to raise the water therein to a sufficient height to insure perfect immersion of the propeller-wheel D, which operates 100

in chamber A from rotary motion imparted to it by shaft E and connections, as herein-after described.

The shaft E is here shown as in connection 5 with crank J, as that of an ordinary steam-engine, through means of which rotary motion may be given to the said shaft with the required force, though let it be understood that I do not confine myself to that particular 10 agency as a motive power, but reserve the right to employ any other force in connection with said shaft for purposes indicated, preferring in all cases to make the same a contiguous part of the chamber A, or at least to have 15 it so connected therewith that it may be considered a part of the adjustable apparatus here described.

Vacuum-chamber B is supplied near the top with a pipe F, which is intended to connect 20 with a suitable air-pump, by means of which the accumulating air in this chamber, which accompanies water into chamber A, can be taken away at once or as fast as it makes its appearance in this locality.

25 G represents an opening into chamber B, through which steam from the boiler or steam-generator can be introduced under sufficient pressure to expel the air, as in the starting of operations here, through the valve C, after which, with the condensation of the remaining steam, the chambers A and B will naturally fill with water through the open bottom of the former, and thereafter, as above indicated, the incoming air will be exhausted 30 through opening at pipe F.

35 The ends and side walls of chamber A are provided at or near the lower edges with a flange H, which secures the said chamber to

the bottom of the vessel, as shown, whereby this entire apparatus can be removed or adjusted, as circumstances require, so that in many cases the said apparatus may be easily made to fit vessels already constructed or may be changed from vessel to vessel, as in the manner of any other adjustable device. 40 However, where it happens that a vessel can be specially constructed to better carry out the system of propulsion herein proposed, then, of course, it might not be so essential to adhere so closely to this adjustable feature 45 of the apparatus under description; but in any event, inasmuch as the chamber A has to be secured to the bottom of the vessel as a rising departure therefrom, I can see no reason why I should materially change this description to meet this last condition. 50

Therefore what I claim as my invention, and desire to secure by Letters Patent of the United States, is—

In means for propelling vessels, an arched 60 chamber in the bottom thereof extending upwardly and above the normal water-line and containing a propeller-wheel, a superposed secondary or vacuum chamber connected to the upper portion of said first-named chamber, and means for partially exhausting said vacuum-chamber for maintaining the water at the desired height therein to insure complete immersion of the propeller-wheel, substantially as described. 65

In testimony whereof I affix my signature in presence of two witnesses.

CHARLES M. COEN.
